UNITED STATES PATENT OFFICE.

JOHN L. SOMMER, OF NEWARK, NEW JERSEY, ASSIGNOR TO J. L. SOMMER MANUFACTURING CO., A CORPORATION OF NEW JERSEY.

FOLDING SHOE-HORN.

1,242,615.

Specification of Letters Patent.

Patented Oct. 9, 1917.

Application filed February 10, 1915. Serial No. 7,241.

To all whom it may concern:

Be it known that I, JOHN L. SOMMER, a citizen of the United States, and a resident of Newark, in the county of Essex and 5 State of New Jersey, have invented certain new and useful Improvements in Folding Shoe-Horns, of which the following is a specification.

The objects of this invention are to provide a shoe horn which can be folded into small compass when not in use; to secure a strong hinged connection of the handle and blade without interfering with the use of the shoe horn; to resiliently hold the parts 15 in open or closed position; to employ a spring for this purpose which is easily constructed and readily applied; to utilize the spring to limit movement of the handle as the same is folded onto the horn; to secure 20 simplicity of construction and operation, and to obtain other advantages and results as may be brought out in the following description.

Referring to the accompanying drawings, 25 in which like numerals of reference indicate the same parts throughout the several views,

Figure 1 is a side view of a folding shoe horn constructed in accordance with my 30 invention and open ready for use;

Fig. 2 is a similar view showing a certain side plate cut away;

Figs. 3 and 4 are views similar to Fig. 2, showing the device in partially closed and 35 entirely closed positions respectively;

Fig. 5 is a longitudinal section on line A—A of Fig. 1;

Fig. 6 is a similar section of the device closed, and

Fig. 7 is a detail perspective view of the spring.

In the specific embodiment of the invention illustrated in said drawings, the reference numeral 1 indicates a shoe horn blade having a large rounded end 2 and a small end 3, with the longitudinal edges 4 converging from said large end to the small one. Preferably the blade is transversely concave between its longitudinal converging 45 edges, as is common in shoe horns, and also said blade curves longitudinally with its side which is transversely concave longitudinally convex and its side which is transversely convex longitudinally concave.

50 A handle member 5 is hinged flatwise

upon the narrow end 3 of the blade 1, at the longitudinally concave side thereof, and preferably the opposite edges 6, 6 of said handle member converge toward its free end substantially in alinement with the converging edges 4, 4 of the blade, as shown. Said handle member is adapted thereby to be swung upon its hinge pin 7, and in order to allow it to close and lie closely adjacent to the blade 1, said handle member 55 is curved longitudinally upon substantially the same radius of curvature as the blade and in the same direction. Preferably a side plate 8 overlies the side of the hinged end of the handle member, said side plate 70 being substantially parallel to the end 3 of the blade, and preferably having a lateral connecting web 9 at one edge joining the said side plate to one longitudinal edge 4 of the horn, preferably integrally. It 75 will be noted that the side plate 8 is upon the side of the blade which is longitudinally concave, so that the opposite side will present a smooth surface against which one's heel may slide in the use of the device. As 80 shown, the side plate 8 preferably extends only a small portion of the length of the blade 1, and is adapted at its inner end, or end nearest the large end 2 of the blade, to engage one's shoe in use and limit sliding of the device down into the shoe as the foot is slid inward. The hinge pin 7 extends through both the side plate 8 and the blade 1, and carries the handle member intermediate thereof, so that said handle 85 member is securely mounted and prevented from any material lateral movement, and yet since the side plate 8 is connected to the blade at one longitudinal edge only the handle member may be swung through 90 180°, from extended position as shown in Figs. 1 and 2 to folded position as shown in Fig. 4.

Preferably the handle member 5 is constructed to have some other utility in addition to its function as a handle, and to this end I have shown the same providing a hook 10 at its free end whereby the same may be used as a button hook, but obviously the handle may be constructed in any shape 100 to adapt it to any desired use. The handle member is shown as cut longitudinally inward from its hinged end upon opposite sides of its hinge pin 7, forming opposite notches 11, 12 thereat, and by virtue of 105 110

these notches 11, 12 transverse shoulders are formed facing toward the pivot end of said handle member, the parts being so positioned and proportioned that one of these 5 shoulders acts as a stop 13 adapted to engage the end of the web 9 when the handle member is swung to its open or extended position, as in Figs. 1, 2, and 5.

Means are preferably provided for 10 silently retaining the handle member at either its open or closed position, said means forming a material part of the present invention. To this end the longitudinal edge 4 of the blade and the corresponding edge 15 of the side plate 8 are slotted, as at 14 adjacent the inner end of the side plate, said slot extending through the web 9 of the side plate. A leaf spring 15 is provided, which is narrow enough to be inserted edge-wise 20 between the said plate and blade through the slot 14, and at its outer end the spring is provided with a head 16 adapted to lie in said slot 14 and limit the inward movement of said spring. In assembling 25 the device, the spring is inserted through said slot, and then pressed or bent toward the connecting portion or web 9 of the side plate, so that its free end extends toward the adjacent or small end of the blade. The 30 handle member is then mounted in position with the leaf spring between the notched end of said member and the web 9 of the side plate. The slot 14 is narrow enough, with respect to the head 16 of the spring, so that 35 the spring is necessarily bent when thus assembled, and presses resiliently against said end of the handle member. Furthermore, the notches provide substantially straight edges longitudinally of the handle member, 40 so that the leaf spring will seat thereagainst and will resiliently resist any tendency to swing the handle member. This construction affords a neat and highly efficient means for holding the handle member in 45 position, and is easily manufactured and assembled.

A closing stop is provided at the opposite side of the narrowed end of the handle member from the stop 13 above described, 50 said closing stop being here shown as the shoulder 17 formed by cutting the notch 11 and is adapted to engage the spring intermediate of its ends when the handle member is swung into closed position. At the same 55 time, the free end of the spring engages the longitudinal edge of the notch, so that said spring operates not only to resiliently resist the opening of the handle member, but also resiliently limits the inward movement 60 thereof, so as to retain the handle member longitudinally of the horn in proper closed position. It is to be noted that when so

closed, the handle member lies closely adjacent the blade, in contact therewith, and the hook 10 is entirely protected so as not 65 to engage and tear one's clothes when carried in the pocket or the like.

Obviously detail modifications may be made in manufacturing my improved folding shoe horn without departing from the 70 spirit and scope of the invention, and I do not wish to be understood as limiting myself except as required by the following claims when construed in the light of the prior art.

Having thus described the invention, what 75 I claim is:

1. In a folding shoe horn, the combination with a blade having a side plate at one end of one of its lateral edges substantially parallel to the body of the blade, said side plate being shorter than the blade and exposing its other end for use, a handle member hingedly mounted between said side plate and the body portion of the blade and adapted to be swung into open or closed position, and a leaf spring supported between the body of the blade and the side plate adapted to engage said handle member and resiliently retain the same in either open or closed position. 90

2. In a folding shoe horn, the combination with a longitudinally curved blade having a side plate at one end of itself on the concave side thereof and connected thereto by a transverse web along one longitudinal edge of the blade, said side plate being shorter than the blade and exposing its other end for use, a handle member hingedly mounted between said side plate and the body portion of the blade and curved in the 100 same direction and upon substantially the same radius of curvature as said blade, whereby in closed position said handle member may be folded to lie closely adjacent the blade. 105

3. In a folding shoe horn, the combination with a blade having a side plate at one end substantially parallel thereto, a transverse web connecting said side plate and blade along one longitudinal edge of the blade, 110 said blade plate and web being slotted, a handle hingedly mounted between said side plate and blade, and a spring between said side plate and blade having a laterally enlarged head in said slot too large to pass between said blade and plate through said slot and engaging at its opposite end the said handle to resiliently retain the same in either extended or closed position. 115

JOHN L. SOMMER.
